CLAIM

The ornamental design for a wall panel, as shown and described.

DESCRIPTION

FIG. 1 is a front perspective view of a first embodiment of a wall panel showing our new design;

FIG. 2 is a front view of the wall panel of FIG. 1;

FIG. 3 is a rear view of the wall panel of FIG. 1;

FIG. 4 is a top view of the wall panel of FIG. 1;

FIG. 5 is a bottom view of the wall panel of FIG. 1;

FIG. 6 is a left-side view of the wall panel of FIG. 1;

FIG. 7 is a right-side view of the wall panel of FIG. 1;

FIG. 8 is an enlarged view of the portion of the wall panel identified by area 8 in FIG. 6;

FIG. 9 is a front perspective view of a second embodiment of a wall panel;

FIG. 10 is a front view of the wall panel of FIG. 9;

FIG. 11 is a rear view of the wall panel of FIG. 9;

FIG. 12 is a top view of the wall panel of FIG. 9;

FIG. 13 is a bottom view of the wall panel of FIG. 9;

FIG. 14 is a left-side view of the wall panel of FIG. 9;

FIG. 15 is a right-side view of the wall panel of FIG. 9;

FIG. 16 is an enlarged view of the portion of the wall panel identified by area 16 in FIG. 14;

FIG. 17 is a front perspective view of a third embodiment of a wall panel;

FIG. 18 is a front view of the wall panel of FIG. 17;

FIG. 19 is a rear view of the wall panel of FIG. 17;

FIG. 20 is a top view of the wall panel of FIG. 17;

FIG. 21 is a bottom view of the wall panel of FIG. 17;

FIG. 22 is a left-side view of the wall panel of FIG. 17;

FIG. 23 is a right-side view of the wall panel of FIG. 17;

FIG. 24 is an enlarged view of the portion of the wall panel identified by area 24 in FIG. 22;

(Continued)

FIG. 25 is a front perspective view of a fourth embodiment of a wall panel;
 FIG. 26 is a front view of the wall panel of FIG. 25;
 FIG. 27 is a rear view of the wall panel of FIG. 25;
 FIG. 28 is a top view of the wall panel of FIG. 25;
 FIG. 29 is a bottom view of the wall panel of FIG. 25;
 FIG. 30 is a left-side view of the wall panel of FIG. 25;
 FIG. 31 is a right-side view of the wall panel of FIG. 25;
 FIG. 32 is an enlarged view of the portion of the wall panel identified by area 32 in FIG. 30;
 FIG. 33 is a front perspective view of a fifth embodiment of a wall panel;
 FIG. 34 is a front view of the wall panel of FIG. 33;
 FIG. 35 is a rear view of the wall panel of FIG. 33;
 FIG. 36 is a top view of the wall panel of FIG. 33;
 FIG. 37 is a bottom view of the wall panel of FIG. 33;
 FIG. 38 is a left-side view of the wall panel of FIG. 33;
 FIG. 39 is a right-side view of the wall panel of FIG. 33; and,
 FIG. 40 is an enlarged view of the portion of the wall panel identified by area 40 in FIG. 38.

The wall panel includes a symbolic break along its length that forms no part of the claimed design. The symbolic break lines and the area between the symbolic break lines form no part of the claimed design. The dash-dash broken lines in the drawings depict portions of the wall panel that form no part of the claimed design. The dash-dot-dash broken lines represent boundaries of the enlarged views and form no part of the claimed design.
